F. V. WINTERS

SPARK PLUG

Filed April 27, 1923

Inventor:

Frederick V. Winters

UNITED STATES PATENT OFFICE.

FREDERICK V. WINTERS, OF NEW YORK, N. Y.

SPARK PLUG.

Application filed April 27, 1923. Serial No. 634,973.

To all whom it may concern:

Be it known that I, FREDERICK V. WINTERS, a citizen of the United States, residing at New York, in the county and State of New York, have invented certain new and useful Improvements in Spark Plugs, of which the following is a full, clear, and exact specification.

This invention relates to spark plugs, and has for its object to provide a plug which may be manipulated for cleaning off accumulations of carbon from the electrodes without removing the plug from an engine.

A special object of the invention is to provide electrodes of improved construction for spark plugs, one of which being stationary and the other movable, the movable electrode being placed above the stationary so that the same may be pressed down and turned in any direction for the purpose of dislodging carbon deposits.

Another object is to form the lower electrode in such a way as to prevent the settling and accumulation of carbon on the points and surface thereof and for its disposal, and also to facilitate the removal of carbon in the event of any deposit thereof interfering with the proper and constant sparking required—which is assured by pressing down the upper electrode into contact with the lower electrode and turning the said upper electrode in any direction, as for instance from left to right or right to left.

A further object of the invention is to provide each of the electrodes with a plurality of sparking points or branch electrodes; the number of said points or branches on the upper electrode differing from the number of such points or branches on the lower electrode—whereby the possibility of the interlocking of said points or branches of one electrode with the points of the other electrode during the operation of the upper electrode when operated for cleaning both electrodes at the same time, is eliminated.

Another object is to provide a plug that can be cleaned without removal, in a moment of time. Other objects will appear as the description proceeds.

The invention will be first hereinafter described in connection with the accompanying drawings, which constitute part of this specification, and then more specifically defined in the claims at the end of the description.

In the accompanying drawings wherein similar reference characters are used to designate corresponding parts throughout the several views:

Figure 1 is a central vertical section of a spark plug constructed substantially in accordance with my invention.

Figure 2 is a bottom plan view of the same.

Figure 3 is a detailed top plan view of the stationary electrode.

Figure 4 is a section on the line IV—IV of Figure 3, and,

Figure 5 is a section on the line v—v of Figure 3.

The spark plug has an outer metallic member 1 screw threaded at 2 to engage the cylinder or head of an internal combustion engine, (not shown) in the usual way. Said member 1 is internally stepped at 3 to support the annular flange or rib 4 of the insulating lining of the plug. Said lining is secured in place by a thimble 6 screwed into the upper end of the member 1. A gasket 7 is placed between the lower end of the thimble 6 and the flange 4 of the lining, and another gasket 8 is preferably placed between said thimble and the upper end of said member 1.

The upper portion of the insulation piece 5, which extends above the thimble 6, is bored at 9 to receive the shaft 10 of the movable electrode. The lower end portion of said shaft 10 is threaded at 11 and a disk shaped nut or adjusting means 12 having a semispherical seat is adjustably mounted thereon to fit and engage an annular ledge or abutment 13, which is formed at the junction of the bore 9 in the upper portion of the insulation piece 5 and the enlarged bore or cylindrical chamber 14 in the lower portion of said insulation piece. Radiating branches 15 are arranged on the lower end of the shaft 10 and constitute the sparking points of the upper or movable electrode. Said branches or points 15 are arranged within the lower bore or chamber 14 of the insulation piece 5, the latter extending down to the lower end of the member 1.

The shaft 10 projects for a considerable distance above the upper end of the insulation piece 5, and its upper end is preferably squared at 16 to receive the detachable wheel 17 for operating the shaft 10 and the electrodes arranged at the lower end thereof.

Below said squared end, the shaft 10 is threaded at 18 to receive an adjustable nut 19, and below said nut 19, a spring 20 is coiled about the shaft with its upper end bearing against said nut and its lower end engaging the upper one of a pair of loosely fitted washers 21, the lower one of which rests on the upper end of the insulation piece 5. Said washers 21 serve as shown in the drawings, see Figure 1, to bind or clamp the terminal 22 of a conductor wire 23 between them, by reason of the tension or action of spring 20. When valve 12 is seated and nut 19 has been properly adjusted for the required tension, said spring 20 also serves to seat and hold nut 12 firmly on the ledge 13 and, moreover, holds or secures the several correlated parts of the plug in their respective and proper positions. The radiating branches 15 of the upper electrode are spaced and securely supported in position for a proper or desired spark gap between said upper and lower electrodes, by first adjusting nut 12 on thread 11 and nut 19 on thread 18 on shaft 10 to a proper tension.

The lower electrode 24, which is secured by screws 25 to the lower end of the member 1, as best shown in Figures 2 and 3, is substantially ring-shaped and has a plurality of inwardly extending points 26, preferably four in number and arranged at equal distances apart around the ring. Said points are segmental in form and have their upper faces rounded at 27 to facilitate removal of carbon when the upper electrode is manipulated as hereinafter explained. The radiating branches or points 15 on the upper electrode are preferably three in number, but it should be understood that the number of said branches 15 as well as the number of the points 26, may be varied if desired. The number of branches 15 should, however, differ from the number of points 26, so that when the lower electrode is engaged by the upper electrode there will be no danger of said branches 15 interlocking with said points 26.

When it is desired to clean the spark plug or remove any accumulated carbon from the branches 15 of the upper electrode and also from the points 26 of the lower electrode, the shaft 10 is depressed by hand, pressing on wheel 17 until said branches 15 are in contact with said points 26, then said shaft 10 and branches 15 are rotated in either direction in order to quickly and assuredly dislodge from both the upper and lower electrode, any carbon deposits thereupon and therefrom. While it is impossible for the branches 15 of the upper electrode to become interlocked with the points 26 of the lower electrode, said branches 15 may reach approximately half way down on the

rounded surfaces 27 of said points 26, or to the points indicated at 28 in Figure 5, whereby said branches 15 will engage and pass over a considerable portion of said rounded surfaces 27 of said points 26, thus facilitating the removal of the carbon therefrom, which carbon will fall through the openings 24 in the lower electrode between the points 26. It will be understood that the shaft 10 is depressed against action of the spring 20, and that said shaft is rotated for cleaning the surfaces, while the branches 15 are in contact with the points 26 of the lower electrode in order to remove the accumulations of carbon from said branches and points. The hand wheel or disk 17 may be removed from the upper end of the shaft 10 and replaced whenever the sparking points require cleaning. If said wheel were permanently attached to the shaft 10 it would become too hot for use for the purpose described.

I claim:

1. In a spark plug, the combination with a stationary electrode having a plurality of radially arranged sparking points, of an axially movable and rotatable electrode having a different number of radiating sparking points for the purpose specified.

2. In a spark plug, the combination with a stationary electrode having a plurality of radiating sparking points, each being of segmental form and having its upper surface rounded, of an axially movable and rotatable electrode arranged above said stationary electrode and having a plurality of radiating sparking points to cooperate with those on the stationary electrode.

3. In a spark plug, the combination with a stationary electrode having a plurality of radially arranged sparking points each of segmental form and having its upper surface rounded, of an axially movable and rotatable electrode having a plurality of radiating sparking points, there being a less number of points on the movable electrode than on the stationary electrode for the purpose specified.

4. In a spark plug, the combination with an axially movable and rotatable electrode, a ring-shaped lower electrode having a plurality of inwardly extending points arranged at equal distances apart around said ring, said points being segmental in form and having their faces rounded, and openings formed therein between said rounded points for receiving the carbon, dislodged from the said rounded points by the operation of the axially movable and rotatable electrode, as specified.

In testimony whereof I have signed my name to this specification.

FREDERICK V. WINTERS.
